UNITED STATES PATENT OFFICE

ANTONIO CORDIO, OF FITCHBURG, MASSACHUSETTS, ASSIGNOR OF ONE-HALF TO
SEBASTIAN GERANTE, OF FITCHBURG, MASSACHUSETTS

WASHBOARD

Application filed July 12, 1929. Serial No. 377,647.

The principal object of my invention is to provide a strong and durable washboard, the rubbing surface of which is preferably of wood to avoid rust getting on the washed 5 material.

A feature of my invention is a rubbing surface, preferably consisting of wooden spindles and another feature is the mounting of these spindles so that they may move bodily. 10 Another feature is that my washboard is reversible and may be used at either side and in this connection I provide a reversible splash member.

Another feature is a reversible breast 15 board.

Other features will be pointed out below.

In the drawing:

Figure 1 is an elevation, partly in section, 20 of a washboard embodying my invention; Figure 2 is a section on line 2—2 of Figure 1;

Figure 3 is a section on line 3—3 of Figure 1; and

Figure 4 is a partial bottom plan of the 25 breast board.

The two side pieces 1 and 2 are alike and description of one of them will suffice. Side piece 1 is of wood and has grooves 3, 4 and 5, recess 6, several perforations referred to 30 below and drip groove 7. Side pieces 1 and 2 are held together at the top by bolt 8 and nuts 9 and 10, the bolt 8 being screw-threaded at both ends to engage said nuts and passing through perforations in the side pieces 35 1 and 2. A similar bolt 11 and similar nuts 12 and 13 hold the side pieces together near the bottom.

Each one of a plurality of solid wooden 40 spindles 14, circular in cross-section, has one end in the recess 6 of side piece 1 and its other end in the corresponding recess of side piece 2. The sum of the diameters of all the spindles is slightly less than the distance between the bolts 8 and 11 so that the spindles 45 are free to rotate but are held against undesired removal. The length of each spindle is slightly less than the distance between the inner walls of the recesses 6. The result is that when the clothing or other material 50 is rubbed over the spindles the latter are

free to rotate so as to bring constantly new portions of the wood in contact with the material and are free to move bodily up and down to a slight extent thus allowing a certain amount of give between the spindles and 55 material and permitting slight relative movement between adjacent spindles to permit the passage of soapy water between them. The rolls are exposed at both the front and rear of the device so that the device may be re- 60 versed for rubbing purposes.

A metal splash member has a main portion 15 extending across the device and an integral flange 16, the portion 15 entering the grooves 5 in the side pieces, as shown in 65 Figure 2, and the flange 16 engaging the top of the side pieces to limit the downward movement of the metal member.

The breast board 17 is of wood and has suitably attached to it near one edge of its under side a metal member 18, the latter having an integral flange 19 which enters groove 3, the flange 19 being perforated so that screw 20 may pass through the perforation in the flange 19 and also through registering 75 perforations in the side piece 1. Nut 21 holds the screw in place. The perforation in flange 19 is slightly larger than the diameter of screw 20 so that flange 19 is free to swing on screw 20 as a pivot. A similar 80 metal member 22 is attached near the other edge of the under side of the breast board 17 and its flange is similarly pivoted on screw 23. The breast board is provided with countersunk finger holes 24 to aid in swinging the breast board on its pivots. When the breast board is in normal position, as shown in Figure 1, it is held in place by a cotter pin 25 passing through a perforation in flange 19 and through registering perforations in 90 side piece 1. A similar cotter pin 26 passes through the flange of member 22. The breast board, in its normal position, prevents the splash member from rising.

As shown in Figure 2, the material is to be rubbed at the side which is at the left in that figure. If it is desired to reverse the device so that the splash member may be in operative position at the other face of the washboard the cotter pins are removed, the 100

breast board is swung into the dotted line position of Figure 2, the splash member 15 is withdrawn from groove 5 and replaced in groove 4 with its flange 16 then extending to the right in Figure 2. The breast board is then swung back into the full line position of Figure 2 and the cotter pins are re-inserted in position.

What I claim is:

- 10 1. A washboard comprising a rubbing surface; two side pieces supporting said surface, each of said side pieces having three grooves corresponding to those of the other side piece; a splash member adapted to be mounted in the two corresponding grooves on the side pieces when said member is to be used in relation to said rubbing surface at one face of the washboard and adapted to be mounted in two other corresponding 20 grooves in the side pieces when said member is to be used in relation to the rubbing surface at the other face of the washboard; and a breast board having flanges pivotally mounted in the third grooves of the side 25 pieces, said breast board, when in normal position, preventing removal of said splash member.
2. A washboard comprising a frame having side pieces, each side piece having a 30 groove; a splash member having a portion to removably enter said grooves and having a flange to engage the tops of said side pieces; and a breast board pivotally mounted on said frame and, when in normal position, preventing removal of said splash member from said 35 grooves.
3. A washboard comprising a frame having side pieces, each side piece having a 40 groove; a splash member having a portion to removably enter said grooves and having a flange to engage the tops of said side pieces; and a breast board pivotally mounted on said frame and, when in normal position, preventing removal of said splash member from 45 said grooves; and means to lock said breast board.
4. A washboard comprising a frame having side pieces, each side piece having a 50 groove; a splash member having a portion to removably enter said grooves and having a flange to engage the tops of said side pieces; and a breast board having finger holes for swinging it, said breast board being pivotally mounted on said frame and, when in normal position, preventing removal of said splash member from said grooves.

ANTONIO CORDIO.
